(57) **CLAIM**

The ornamental design for a pop-up window for a touch-based user interface for an image processing machine, as shown and described.

DESCRIPTION

The single FIGURE is a front view of a pop-up window for a touch-based user interface for an image processing machine showing the design.

The broken line drawing of a touch-based user interface for an image processing machine is shown for illustrative purposes only and forms no part of the claimed design.
